CLAIM

The ornamental design for a paint roller frame, as shown and described.

DESCRIPTION

FIG. 1 is a front elevational view thereof;

FIG. 2 is a rear elevational view thereof;

FIG. 3 is a bottom view thereof;

FIG. 4 is a top view thereof;

FIG. 5 is an inverted, left side elevational view thereof; and,

FIG. 6 is an inverted, right side elevational view thereof.

The broken line showing of a paint shield and a handle is for illustrative purposes only and forms no part of the claimed design.
